(57) **CLAIM**

The ornamental design for a shoe sole, as shown and described.

DESCRIPTION

FIG. 1 is a left-side view of a shoe sole in accordance with our new design;

FIG. 2 is a right-side view thereof;

FIG. 3 is a front view thereof;

FIG. 4 is a rear view thereof;

FIG. 5 is a top view thereof;

FIG. 6 is a bottom view thereof; and,

FIG. 7 is a bottom perspective view thereof.

The broken lines shown in the figures show portions of the shoe sole that form no part of the claimed design.

1 Claim, 6 Drawing Sheets
